Apparatus for treating flowable solids, such as foundry sand, and the like, which apparatus includes a rotary louvre cooler for cooling the material while it is being screened, and a discharge end for receiving the cooled material and discharging the same.

UNITED STATES PATENT OFFICE

2,452,362

APPARATUS FOR TREATING FLOWABLE SOLIDS

John L. Erisman, Oak Park, Ill., assignor to Link-Belt Company, a corporation of Illinois

Application December 19, 1944, Serial No. 568,859

4 Claims. (Cl. 22—89)

1 This invention relates to new and useful improvements in apparatus for treating flowable solids, and deals more specifically with apparatus which will screen and cool such solids and effect separation and removal of dust, or other fines.

Although this apparatus is suitable for treating many different materials and for use as a primary cooler, if the temperature reduction desired is not too great, it specifically will be described in connection with its use as a screening and auxiliary cooling unit for foundry sand being reconditioned or reclaimed.

The patent to Hartley and Whitehead, No. 2,326,218, issued August 10, 1943, discloses and claims a method of and apparatus for reclaiming foundry sand, and particularly core sand, so that it will be suitable for re-use. This patented method and apparatus includes the steps of heating the used core sand to within a temperature range of from 500° to 1500° F. to drive off the burnt and spent binder materials and other foreign matter adhering to the sand grains; then passing the hot sand through a rotary, internal louvre cooler of the type broadly covered by the patent to Bojner and Pehrson, No. 1,709,456, issued April 16, 1929; and finally screening the sand to remove all oversize material and delivering the reclaimed sand grains of proper size to a belt conveyor which carries it to storage or to the proper location in the foundry for immediate re-use.

The rotary, louvre cooler employed in the above noted patented method, of course, can be provided of a proper size to effect any temperature reduction that is necessary to condition the sand for safe handling by a belt conveyor, or for storage or immediate re-use. It has been determined, however, that a considerable saving in the total cost of this type of sand reclaiming installation can be effected by employing a rotary, louvre cooler of a size which is capable of reducing the temperature of the sand only to a value which will permit it to be handled safely by a vibrating screen and by effecting the final temperature reduction while screening out the oversize material and effecting the removal of the dust resulting from the screening operation.

It is the primary object of this invention to provide an inexpensive, compact unit which is capable of screening and cooling flowable solids and removing the dust that results from the screening operation, as will be more fully set forth hereinafter. A further important object of the invention is to provide apparatus of the above-mentioned type which employs a single forced flow of air

for cooling the material both while it is being screened and after it has passed through the screen; for assisting in maintaining the material in a loose or unpacked condition while in engagement with the screening surface to facilitate separation of dust, and for carrying off the separated dust.

In sand reclamation installations of the above noted type, the temperature reducing capacity of a given size of rotary, louvre cooler can be increased by spraying water onto the sand passing therethrough. The sand discharged from a rotary cooler of this type carries with it some moisture when it is discharged.

15 A further primary object of the invention is to utilize the forced flow of cooling and dust removing air to drive off this moisture from the sand while it is being screened and cooled.

Other objects and advantages of the invention will be apparent during the course of the following description.

In the accompanying drawings forming a part of this specification, and in which like numerals are employed to designate like parts throughout the same,

20 Figure 1 is a side elevational view of the flowable solids treating apparatus embodying this invention.

Figure 2 is a front elevational view of the apparatus disclosed in Fig. 1, showing certain features.

Figure 3 is an enlarged vertical sectional view taken on line 3—3 of Fig. 2.

Figure 4 is a vertical sectional view taken on line 4—4 of Fig. 3.

Figure 5 is a top plan view, partly broken away, of the apparatus disclosed in Figs. 3 and 4.

Figure 6 is a detail, horizontal sectional view taken on line 6—6 of Fig. 3, section A-A.

Figure 7 is an elevational view of the fragmentary portion of the apparatus disclosed in Fig. 6.

Figure 8 is a detail vertical sectional view taken on line 8—8 of Fig. 6.

In the drawings, wherein for the purpose of illustration is shown the preferred embodiment of this invention, and first particularly referring to Figs. 1 and 2, the reference numeral 10 designates the discharge end of a rotary, louvre cooler of the type disclosed in the aforesaid patent to Bojner and Pehrson. This unit constitutes the primary cooler of the flowable solids treating apparatus when this apparatus is employed as a part of an installation for reconditioning or reclaiming foundry sand. The solids discharged

25 from the rotary cooler 10 are received by the

hood 11. This hood is provided with a material discharge chute 12, through which the partially cooled solids are delivered, and an exhaust duct 13, through which the spent cooling medium and the liberated dust is drawn from the hood 10 and delivered to a stack, or other means of disposal.

The discharge chute 12 is suitably connected to an extension 14 that is illustrated in Figs. 3 and 5 as being connected to and extending into a stationary cover, or exhaust hood, 15. This exhaust cover or hood is properly shaped to provide an exhaust opening 16 for connection with an exhaust duct 17 that is shown in Figs. 1 and 2 as extending to and communicating with the exhaust duct 13 of the primary cooler discharge hood 11.

Positioned beneath the exhaust cover or hood 15, and telescopically associated with the base flanges 15a of the cover or hood 15, is a vibrating screen that is designated in its entirety by the reference character 18. This vibrating screen may be of any desired conventional type but for the purpose of this disclosure it is illustrated as consisting of a screen box 19 that is supported for vibratory movements by the leaf springs 20. A screen cloth, of appropriate mesh, 21 is properly positioned within the screen box 19. A belt driven vibrator unit 22 is suitably attached to the screen box 19. Fig. 1 discloses a motor 23 for driving this vibrator unit.

Suitably attached to the screen box 19, and forming therewith a composite vibrating structure, is a pan 24. This pan is of box-like construction for it includes suitable side and end walls.

Figs. 3 and 4 disclose the pan 24 as being provided with an inclined bottom wall structure 25. This bottom wall structure is intended to allow for the passage of air therethrough and to cause the solids to cascade thereover so as to be subjected to the air that passes through this wall structure. One construction that will accomplish these two functions is illustrated as consisting of a series of spaced, partially overlapping or stepped louvre plates 26. It will be noted that this bottom wall structure bridges all of the interior of the pan with the exception of a portion that is left at the bottom of the inclined wall structure to provide a discharge opening 27. It will be noted that this discharge opening underlies the discharge end portion of the screen cloth 21.

Figs. 3 and 4 disclose in detail a stationary hopper 28 that is positioned beneath the pan 24. This hopper is formed with the side walls 29 and 30, see Fig. 4, the front wall 31, the rear wall 32, and the inclined bottom wall 33, see Fig. 3. The open top of this hopper 28 corresponds in dimensions with the bottom of the pan 24 and a canvas, or other flexible material, seal 34 closes the space between the hopper and the pan to prevent the leakage of air and dust while allowing the pan to vibrate relative to the stationary hopper. This hopper is provided with a discharge opening 35 that communicates with a discharge chute 36. It will be noted by inspecting Fig. 3 that the discharge opening 35 of the hopper is vertically aligned with the discharge opening 27 formed in the bottom wall structure 25 of the pan 24.

An opening 37 is formed in the front wall 31 of the hopper. The discharge end of the cold air duct 38 is suitably attached to the margins of this opening 37. This duct is illustrated in

Figs. 1, 2 and 3 as being connected to the outlet of the blower 39 that is driven by the motor 39a.

This cold air duct 38 is illustrated in Figs. 3 and 6 to 8 inclusive as including an elbow portion 38a. To cause the flow of air to be uniform throughout the cross section of this elbow, a series of parallel partition walls 38b are arranged within the bore of the elbow. These partition walls are shown in Fig. 6 as terminating at the discharge end of the elbow 38a, or at the entrance to the air inlet opening 37 of the hopper 28.

Figs. 3, 4 and 6 disclose a series of vanes 40 as being attached to the front wall 31 of the hopper in alignment with the air inlet opening 37 formed in this wall and with the discharge end of the cold air duct elbow 38a. It will be noted by inspecting Fig. 3 that the outer edges of these vanes 40 are stepped and that these vanes 20 lie in the path that extends between the discharge opening 27 of the pan bottom wall structure 25 and the discharge opening 35 at the bottom of the hopper 28.

The discharge chute 36 of the hopper 28 is intended to deliver the completely cooled solids to a conveyor which will carry the solids, such as reclaimed core sand, to a storage bin or to a proper place for immediate use.

Figs. 1 to 4 inclusive disclose the discharge chute 36 as delivering the solids to the upper, or active, run 41 of a belt conveyor. This belt conveyor is illustrated in Figs. 2 and 4 as being trained over an end roll 42. Suitable idler roll assemblies, not shown, will be provided for properly supporting the runs of the belt conveyor during the remainder of their paths of travel. Figs. 3 and 4 disclose in detail a supporting plate 43 which underlies the top run 41 of the belt conveyor where it receives the solids from the discharge chute 36 of the hopper 28.

It is deemed advisable to enclose the reclaimed sand, or other cooled solids, while they are being conveyed away by the upper run 41 of the belt conveyor. For this reason, a housing overlies the active run of the conveyor. This housing includes the cover plate 44 and the side skirts 45. A canvas, or other flexible material, sealing strip 46 depends from the bottom edge of each of the side skirts 45 and the hopper discharge chute 36. 50 Seal off curtains 47 depend from the cover plate 44 of the casing that overlies the active run 41 of the conveyor belt. These curtains may be made of canvas, or other flexible material, and function to prevent loss of cold air down the path of the conveyor.

Figs. 1, 3 and 5 illustrate a refuse chute 48 as being connected to the exhaust cover or hood 15 in a proper position to receive the oversized material discharged as tailing from the vibrating screen. A back suction closure gate 49 is provided for the chute 48. This gate is kept closed by the air suction created in the chute 48 as a result of the flow of air upwardly through the vibrating screen and the exhaust cover or hood 15. Of course, this gate opens to allow for the discharge of the oversize material when it flows through the chute 48.

By inspecting Fig. 3, it will be seen that the solids are delivered by the feed chute extension 50 onto the receiving end of the screen cloth 21. These solids will move down the screen cloth while sand grains, or other solids of proper particle size, pass through the screen cloth and the oversize material moves on into the refuse chute 48. The 75 solids that pass through the screen cloth fall onto

the louvre plates 26 of the bottom wall structure of the pan 24. The solids are caused to cascade over the louvre plates until they reach the discharge opening 27 when they will be delivered to the hopper 28. In falling through the hopper, the solids will encounter the vanes 40 and will cascade over the outer edges of these vanes until they reach the discharge opening 38 of the hopper. After passing through this discharge opening, the solids will be delivered onto the upper run 41 of the belt conveyor by the hopper discharge chute 36.

The forced supply of cold air is discharged into the interior of the hopper 28 by the duct 38. In leaving the discharge end of the duct elbow 38a, the cooling air will pass between the vanes 40 and will be directed into the stream of solids cascading over these vanes. The cooling air, therefore, will be placed in intimate contact with the solids forming this stream.

After passing through this stream of solids, the cooling air will flow upwardly through the hopper 28. The inclined bottom wall 33 of this hopper will function to direct the flow of air toward the inclined series of louvre plates 26 that form the bottom wall of the pan 24. The air will flow between the louvre plates and through the layer or stream of solids cascading over these plates. This will provide another intimate contact between the cooling air and the solids. After passing through this cascading layer of solids, the air flows upwardly countercurrent to the falling solids from the screen cloth 21. The air, also, will flow through the layer of solids moving over the screen cloth. Therefore, further intimate contact between the cooling air and the solids is provided in the pan 24 and at the surface of the screen cloth. After passing through the solids on the screen cloth, the air moves upwardly into the cover or hood 15 and then into the exhaust duct 17.

It will be appreciated that dust, or fines, will be separated from the solids during the screening operation. The passage of the cooling air through the solids moving over the screen cloth will tend to maintain the solids in a loose, unpacked condition and will consequently assist in the operation of separating dust. This dust will be carried into the cover or hood 15, and the exhaust duct 17, by the upward flow of air from the screen cloth.

In some installations water is sprayed onto the solids passing through the rotary cooler 10 to assist in lowering the temperature of said solids. Such an operation may result in the discharge of moist solids from the hood 11. The flow of cooling air through the solids passing over the screen cloth will drive off this moisture.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. Apparatus for cooling, screening and removing fines from flowable solids, comprising the combination with a rotary primary cooler having a stationary hood provided with chute for discharging the partially cooled solids and a duct for exhausting the spent cooling air, of a vibrating screen receiving the solids from the discharge chute, a pan attached to the bottom of the screen to vibrate therewith, an inclined series of louvres bridging a portion of the interior of the pan and over which screened solids cas-

cade before being discharged from the lower end of the series, a stationary hopper positioned below the pan to receive the solids discharged from the lower end of the series of louvres, said hopper having a discharge opening underlying the unbridged portion of the pan, a blower having a discharge duct located at one side of and opening through the side of the hopper adjacent its discharge opening for delivering a forced draft of cooling air into the hopper so that it will pass first through the stream of solids discharging from the series of louvres, then through the solids cascading over the louvres, and finally through the solids moving over the screen to effect final cooling of said solids, a stationary cover over the vibrating screen to receive the air and suspended fines rising from the solids on the screen, and an exhaust duct connecting the cover to the exhaust duct of the primary cooler.

2. Apparatus for cooling, screening and removing fines from flowable solids, comprising the combination with a rotary primary cooler having a stationary hood provided with a chute for discharging the partially cooled solids and a duct for exhausting the spent cooling air, of a vibrating screen receiving the solids from the discharge chute, a stationary hopper having a bottom discharge opening positioned below the vibrating screen, a pan interposed between the vibrating screen and the hopper and attached to the bottom of said screen to vibrate with the latter, an inclined series of louvres bridging a portion of the interior of the pan and over which screened solids cascade before being discharged from the lower end of the series, means for sealing between the vibrating pan and the stationary hopper to prevent leakage of air, a blower having a discharge duct opening through the side of the hopper for introducing a forced draft of cooling air into the hopper, a series of vanes, having stepped outer edges, positioned in the hopper in alignment with the duct opening and projecting into the vertical path lying between the discharge opening of the hopper and the lower discharge end of the series of louvres, the cooling air being introduced so that it will pass first through the stream of solids discharging from the lower end of the series of louvres, then through the solids cascading over the louvres, and finally through the solids moving over the screen to effect final cooling of said solids, and means overlying the vibrating screen to exhaust the air and suspended fines therefrom.

3. Apparatus for cooling and screening hot foundry sand, comprising a vibrating screen box having a screening surface receiving the hot sand, a pan attached to the bottom of the screen box and underlying the entire screening surface, an inclined series of overlapping, spaced louvres arranged to bridge all of the bottom of the pan with the exception of that portion which underlies the discharge end portion of the screening surface, whereby sand passed through the screening surface will fall onto the louvres and cascade thereover before being discharged from the lower end of the series, a stationary hopper beneath the pan and having a discharge opening underlying the unbridged portion of the pan bottom and an inclined bottom wall underlying the bridged portion of the pan bottom, a duct located at one side of the hopper adjacent to its discharge opening for delivering a forced supply of cooling air across the hopper above its discharge opening and toward its inclined bottom wall, whereby the air will pass first through the sand falling

from the discharge end of the series of louvres, then between the louvres and through the sand cascading thereover, and finally through the sand moving over the screening surface, and means overlying the screen box to exhaust the air and suspended fines from said box.

4. Apparatus for cooling and screening hot foundry sand, comprising a vibrating screen receiving the hot sand, a pan attached to the screen to vibrate therewith, an inclined, stepped wall structure positioned in the pan and having a discharge opening at its lower end, said wall structure having openings for the passage of cooling air, a stationary hopper underlying the pan and having a discharge opening vertically aligned with the discharge opening of the pan wall structure, a forced air duct opening through the side wall of the hopper that is adjacent the said vertically aligned discharge openings so as to discharge the flow of cooling air at right angles to the path lying between said openings, a series of vanes having stepped outer edges, positioned in the hopper in alignment with the air duct opening and projecting into the said path lying

between the discharge openings, the cooling air entering the hopper being directed to flow through the air openings in the pan wall structure and through the vibrating screen, and means overlying the vibrating screen to exhaust the air.
